(57) **CLAIM**

The ornamental design for a connector hub assembly, as shown and described.

DESCRIPTION

FIG. 1 is a top, front, perspective view of the connector hub assembly of the present design;

FIG. 2 is a top plan view of the connector hub assembly of FIG. 1;

FIG. 3 is a bottom plan view of the connector hub assembly of FIG. 1;

FIG. 4 is a front elevation view of the connector hub assembly of FIG. 1;

FIG. 5 is a rear elevation view of the connector hub assembly of FIG. 1;

FIG. 6 is a right, side elevation view of the connector hub assembly of FIG. 1; and,

FIG. 7 is a left, side elevation view of the connector hub assembly of FIG. 1.

In FIGS. 1-7, the features of the connector hub assembly shown in phantom lines are for illustrative purposes only and do not constitute a part of the claimed design.

The broken lines in the drawings illustrate unclaimed portions of the connector hub assembly and form no part of the claimed design.
